GAME

Kenneth J. Gross, Van Nuys, and Sebron Koster,
Los Angeles, Calif.

Application September 23, 1954, Serial No. 457,972

11 Claims. (Cl. 273—134)

This invention relates to games and particularly to 15 game boards which provide a predetermined path along which each player moves his playing piece during the course of the game, the path being divided into a plurality of spaces or segments each having a determining influence on the play, and in which the extent of each 20 player's move is established by chance.

Such games are well-known e.g. "Monopoly," disclosed in U.S. Patent No. 2,026,082, issued December 31, 1935, and the game which provides actions of trading in securities and commodities disclosed in U.S. Patent No. 25 2,666,644, issued January 19, 1954. They have the feature of requiring a certain degree of individual skill to turn chance-determined actions to best advantage.

The present invention is an improvement over such games in that it provides a construction and incorporates 30 devices which enable actions such as that of electing a President of the United States to be simulated. Other objects of the invention are to provide a game which has distinct educational value and in which the play can be influenced by a player in a manner analogous to the 35 strategy used by a party in a presidential election campaign whereby the electoral votes can be acquired in such a way as to start a "landslide" in favor of that party, as the other parties are eliminated.

In order that the principle of the invention may be readily understood we have disclosed a specific embodiment thereof in the accompanying drawings, wherein—

Fig. 1 is a plan view of one form or arrangement of a game board or playing field arranged according to our invention and showing the various segments of the playing path marked to represent each as one of the States of the United States of America and showing as its elements the number of electoral votes of that state.

Fig. 2 is a perspective view of six different markers used by the several players respectively, each representing a specific political party, for registering the location of the respective players on the playing path.

Fig. 3 is a plan view showing typical specimens of a set of cards, there being one such card for each State initially placed beside the segment representing that State on the playing path.

Fig. 4 is a plan view showing typical specimens of a set of tokens representing 1, 5 and 10 electoral votes apiece. Each of the six sets of tokens corresponds to one political party and is distinguished by color from the other sets.

Fig. 5 is a perspective view of the die used to determine the extent of move a player may make along the playing path and the number of votes he acquires on the segment attained.

In the form shown in the drawings, the improved game board 1 is of flat rectangular form and is provided with a circumferential playing path 2 which is closed upon itself and which is divided into a plurality of segments or spaces 3. From the centre of each of the four sides an alternative segmented path 4 is also provided to the

2

centre of the board where it meets the other three alternative paths in a common central segment 5, designated Washington, D.C.

Each of the segments of the playing path is provided 5 with an individual designation as a single State and with the number of electoral votes accorded to that State. The designations are provided in such a manner as to group the States in a roughly geographical arrangement on the playing path. The following is a list of the States 10 giving the number of electoral votes accorded to each:

Western States (11)	Mid-Western States (12)
4 Arizona	27 Illinois
32 California	13 Indiana
6 Colorado	10 Iowa
4 Idaho	8 Kansas
4 Montana	20 Michigan
3 Nevada	11 Minnesota
4 New Mexico	13 Missouri
6 Oregon	6 Nebraska
4 Utah	4 North Dakota
9 Washington	25 Ohio
3 Wyoming	4 South Dakota
79	12 Wisconsin
	153

Southern States (13)	Eastern States (12)
11 Alabama	8 Connecticut
8 Arkansas	3 Delaware
10 Florida	5 Maine
12 Georgia	9 Maryland
10 Kentucky	16 Massachusetts
10 Louisiana	4 New Hampshire
8 Mississippi	16 New Jersey
14 North Carolina	45 New York
8 Oklahoma	32 Pennsylvania
8 South Carolina	4 Rhode Island
11 Tennessee	3 Vermont
24 Texas	8 West Virginia
12 Virginia	153

The following is a list of the political parties indicating the insignia and colors of the corresponding markers and sets of tokens:

Democratic.....	D	Purple.
Independent.....	I	Yellow.
Prohibitionist.....	P	Green.
Republican.....	R	Blue.
Socialist.....	S	Red.
Social Democrat.....	SD	Orange.

At the start of the play of a game each player selects his political party and takes his marker and tokens to match. Each player or candidate rolls the die and the 55 candidate who rolls high die opens the play. He is succeeded in turn by each candidate in a clock-wise direction. All candidates begin their campaign from the central segment, viz. Washington, D.C.

The number appearing on the die indicates the number 60 of segments (States) which the candidate may move his marker and the number of electoral votes he wins in the State attained. He places his marker on that State and beside it his tokens corresponding to the number of votes thereby won in that State.

On each turn a candidate may move in any direction he 65 chooses. The choice of routes allowed to candidates enables them to exert an influence on the development of their campaigns. In passing through a junction of three States he may traverse only two of the States in the course of any one move. He may not reverse his direction of movement in the course of one move. A candidate may not land on nor pass through a State

occupied by another candidate's marker. If the movement of a candidate is blocked by the markers of other candidates in such a manner that he cannot move his marker to the full extent of his throw of the die, then he loses that turn. A candidate must move if possible.

A candidate must return to Washington, D.C. at any time that his throw of the die could place him there, providing that Washington, D.C. is unoccupied.

The number of electoral votes of a State won by a candidate is indicated by his tokens placed alongside that State. The entire electoral vote of a State is won by the first candidate to obtain a majority of the electoral votes of that State. When a State is won by a candidate he removes the card of that State and all the electoral vote tokens on that State are returned to their respective candidates.

States that have not been won are indicated by the presence of the State cards still beside them. Any candidate may land on a State that has been won by another candidate irrespective of the presence or absence of electoral votes remaining unacquired.

Whenever a candidate lands on Washington, D.C., he has the right to call a "caucus" if he so desires. When a caucus is declared all candidates count the electoral votes of the States they have won completely, as indicated by the State cards in their possession. The outstanding electoral votes relating to States not yet won are also counted. Should the candidate with the least number of electoral votes be unable to win the election even by winning all the electoral votes of the States which are not yet won completely then he is eliminated as a presidential candidate. Only one candidate may be eliminated on each caucus.

If on the calling of a caucus, the tally of electoral votes indicates that every candidate still has a chance to win the election assuming his acquisition of all outstanding electoral votes, then the candidate calling the caucus loses all his electoral votes on States not won completely; that is he removes all his electoral vote tokens from the board.

The electoral vote tokens of the eliminated presidential candidate on the States not completely won are removed from the board. The electoral votes of the States completely won by the eliminated candidate are divided among the remaining candidates according to the geographical distribution set out in the table above. In other words the candidate with the most electoral votes from the Eastern States, takes all the Eastern States from the eliminated candidate and similarly for the other geographical groups of States.

The presidential election is won by the first candidate who captures 266 or more electoral votes.

Although but one specific embodiment of this invention is herein shown and described, it is intended as illustrative in a generic sense and not for purposes of limitation and it will be understood that variations of the apparatus and the game board shown may be made without departing from the spirit of this invention, the scope of the invention being set forth in the following claims.

We claim as our invention:

1. A board game apparatus comprising a board having a playing path thereon divided into a plurality of segments, said segments having respectively designations for different entities, each said entity being characterized by a predetermined number of elements, a set of individually distinctive playing pieces for registering location of each player on said path, a set, distinctive for each player, of tokens for registering cumulatively for each of said segments the number of said elements acquired by each player, and means for determining by chance the extent of the movement of the playing pieces and the number of elements acquired by each player on each movement, the direction of said movement being open to the choice of the respective player, and incorporating a segment per-

mitting the arbitrary initiation by a player whose playing piece occupies it of a redistribution of the acquired elements and entities depending upon the distribution of the elements at that point in the game.

5 2. A board game apparatus comprising a board having a playing path thereon divided into a plurality of segments, said segments having respectively designations for different entities, each said entity being characterized by a predetermined number of elements, a set of individually distinctive playing pieces for registering location of each player on said path, a set, distinctive for each player, of tokens for registering cumulatively for each of said segments the number of said elements acquired by each player, and means for determining by chance the extent of the movement of the playing pieces and the number of elements acquired by each player on each movement, the direction of said movement being open to the choice of the respective player, and incorporating a segment permitting the arbitrary initiation by a player whose playing piece occupies it of a redistribution of the acquired elements and entities depending upon the distribution of the elements at that point in the game, enabling the players to simulate the prosecution of a presidential election campaign.

20 3. A board game apparatus comprising a board having a playing path thereon divided into a plurality of segments, said segments having respectively designations for different entities, each such entity being characterized by a predetermined number of elements, a set of individually distinctive playing pieces for registering location of each player on said path, a set, distinctive for each player, of tokens for registering cumulatively for each of said segments the number of said elements acquired by each player, and means for determining by chance the extent of the movement of the playing pieces and the number of elements acquired by each player on each movement, each said movement being open to the choice of up to eight directions.

25 4. A board game apparatus comprising a board having a playing path thereon divided into a plurality of segments, said segments having respectively designations for different entities, each such entity being characterized by a predetermined number of elements, a set of individually distinctive playing pieces for registering location of each player on said path, a set, distinctive for each player, of tokens for registering cumulatively for each of said segments the number of said elements acquired by each player, and means for determining by chance the extent of the movement of the playing pieces and the number of elements acquired by each player on each movement, and incorporating a segment permitting the arbitrary initiation by a player whose playing piece occupies it of a redistribution of the elements at that point in the game.

30 5. A board game apparatus comprising a board having a playing path thereon divided into a plurality of segments, said segments having respectively designations for different entities, a set of markers each corresponding in designation to one of the entities, each such entity being characterized by a predetermined number of elements, a set of individually distinctive playing pieces for registering location of each player on said path, a set, distinctive for each player, of tokens for registering cumulatively for each of said segments the number of said elements acquired by each player, and means for determining by chance the extent of the movement of the playing pieces and the number of elements acquired by each player on each movement said movement being open to the choice of up to eight directions.

35 6. A board game apparatus comprising a board having a playing path thereon divided into a plurality of segments, said segments having respectively designations for different entities, each such entity being characterized by a predetermined number of elements, a set of individually distinctive playing pieces for registering location of each player on said path, a set, distinctive for each

player, of tokens for registering cumulatively for each of said segments the number of said elements acquired by each player, and means for determining by chance the extent of the movement of the playing pieces and the number of elements acquired by each player on each movement, the direction of the movement being open to choice, and incorporating a segment permitting the arbitrary initiation by a player whose playing piece occupies it of a redistribution of the acquired elements depending upon the distribution of the elements at that point in the game.

7. A board game apparatus comprising a board having a playing path thereon divided into a plurality of segments, said segments having respectively designations for different entities, a set of markers each corresponding in designation to one of the entities, each such entity being characterized by a predetermined number of elements, a set of individually distinctive playing pieces for registering location of each player on said path, a set, distinctive for each player, of tokens for registering cumulatively for each of said segments the number of said elements acquired by each player, and means for determining by chance the extent of the movement of the playing pieces and the number of elements acquired by each player on each movement, the direction of movement being open to choice and incorporating a segment permitting the arbitrary initiation by a player whose playing piece occupies it of a redistribution of the acquired elements depending upon the distribution of the elements at that point in the game.

8. A board game apparatus comprising a board having a playing path thereon divided into a plurality of segments, said segments having respectively designations for different entities, each such entity being characterized by a predetermined number of elements, a set of individually distinctive playing pieces for registering location of each player on said path, a set, distinctive for each player, of tokens for registering cumulatively for each of said segments the number of said elements acquired by each player, and means for determining by chance the extent of the movement of the playing pieces and the number of elements acquired by each player on each movement, the direction of the movement being open to choice, and incorporating a segment permitting the arbitrary initiation by a player whose playing piece occupies it of a redistribution of the acquired elements and entities depending upon the distribution of the elements at that point in the game, enabling the players to simulate the prosecution of a presidential election campaign.

9. A board game apparatus comprising a board hav-

ing a playing path thereon divided into a plurality of segments, representing States arranged in a geographical sequence each segment being characterized by a predetermined number of elements representing votes, a set of individually distinctive playing pieces for registering location of each player on said path, a set, distinctive for each player, of tokens for registering cumulatively for each of said segments the number of said elements acquired by each player, and means for determining by chance the extent of the movement of the playing pieces and the number of elements acquired by each player on each movement, the direction of the movement being open to choice so as to enable the players to simulate the prosecution of a presidential election campaign.

10. A board game comprising a board having a playing path thereon divided into a plurality of segments representing States arranged in a geographical sequence, a set of markers each corresponding in designation to one of the segments, each segment being characterized by a predetermined number of elements representing votes, a set of individually distinctive playing pieces for registering location of each player on said path, a set, distinctive for each player, of tokens for registering cumulatively for each of said segments the number of said elements acquired by each player, and means for determining by chance the extent of the movement of the playing pieces and the number of elements acquired by each player on each movement, the direction of the movement being open to choice so as to enable the players to simulate the prosecution of a presidential election campaign.

11. A game board apparatus comprising a board having a playing path thereon divided into a plurality of segments, said segments having respectively designations for different entities, each such entity being characterized by a predetermined number of elements, a set of individually distinctive playing pieces for registering location of each player on said path, a set, distinctive for each player, of tokens for registering cumulatively for each of said segments the number of said elements acquired by each player, and means for determining by chance the extent of the movement of the playing pieces and the number of elements acquired by each player on each movement, the direction of the movement being open to choice so as to enable the players to simulate the prosecution of a presidential election campaign.

45 11. A game board apparatus comprising a board having a playing path thereon divided into a plurality of segments, said segments having respectively designations for different entities, each such entity being characterized by a predetermined number of elements, a set of individually distinctive playing pieces for registering location of each player on said path, a set, distinctive for each player, of tokens for registering cumulatively for each of said segments the number of said elements acquired by each player, and means for determining by chance the extent of the movement of the playing pieces and the number of elements acquired by each player on each movement.
